UNITED STATES PATENT OFFICE.

ERNEST A. LOWE, OF PLAINFIELD, NEW JERSEY, ASSIGNOR, BY MESNE ASSIGNMENTS, TO AUTOMATIC SPRINKLER COMPANY OF AMERICA, OF DOVER, DELAWARE, A CORPORATION OF DELAWARE.

AUTOMATIC SPRINKLER HEAD.

Application filed November 30, 1920. Serial No. 427,353.

To all whom it may concern:

Be it known that I, ERNEST A. LOWE, a citizen of the United States, and a resident of Plainfield, in the county of Union and State of New Jersey, have invented certain new and useful Improvements in Automatic Sprinkler Heads, of which the following is a specification.

My invention relates to that class of fire extinguishing devices known as automatic sprinkler heads wherein the hole or orifice through which the fire extinguishing fluid escapes is normally closed by a suitable cap which holds back the fluid in the piping system, said cap or valve being normally held in place by an arm or system of arms or levers held in restraint by a fusible link or mass of fusible material such as a low melting solder alloy.

While there are many shapes and types of sprinkler heads all embodying the same general scheme of construction, the proper functioning of all of them requires that the fusible member melt at a fixed or critical temperature to release the arms or levers and allow fluid to escape from the piping system, for the purpose of extinguishing a fire. Because of inherent limitations, low fluid pressure and slowness of fire detection, the maximum floor space allowed per sprinkler is 100 square feet; in practice, however, this is often reduced to 60 square feet with the consequent increase of piping, apparatus and installation expense.

While typical sprinkler heads are rugged and have been consistent in action, still the fire records for the past twenty years reveal losses due to fire getting beyond the control of a single head and being generally accompanied by heavy water damage, should an excessive number of heads open. This undesirable action is mainly due to the inherent limitations of the standard types of sprinkler heads among which may be mentioned:

(a) They have great lag or delay in action from heat, being of large mass; the fusible member thereby is slow of response to the action of the heat.

(b) The fuse point of the fusible member is not the operating point of the head in practice. A head marked as 165° requires 240 to 250 degrees Fahrenheit of surrounding air temperature, sustained long

enough to heat the entire mass to fusion point of the alloy before it will operate.

(c) They cannot be safely made to respond to temperatures only slightly higher than those normal to the room in which they are to be placed, on account of the decomposing action of the heat upon the alloy used in the fusible member, such decomposition manifesting itself by change in molecular strength, also change in the fusing point, thereby causing premature action or non-action at predetermined fuse point.

(d) They are very susceptible to change in operating constant, due to (1) change of fusible alloy; (2) encrustation; (3) decomposition; and must be specifically made for each different operating temperature—the generally accepted degrees at which sprinkler heads are manufactured being 165°, 212°, 286° and 360° Fahrenheit, neither of which may be substituted for the other. Field experience, as shown in the underwriters' records, reveals that it is common practice and the accepted rule to allow approximately 70° difference between the maximum normal temperatures at which the room reaches and the degree or fusing point of the sprinkler head; a room where the maximum temperature reaches 140° would require a 212° head, while temperatures exceeding 140-160 degrees Fahrenheit would require the next higher degree or 286° head. If the normal temperature exceeds 210° Fahrenheit the 360° head is advocated.

Again, it is obvious that the lower the initial temperature in which any of these sprinkler heads are located the longer they take to operate from a fire, and as the lowest accepted fuse point standard of the typical commercial sprinkler is 155°-165° Fahrenheit, predicated upon its use in normal temperatures, it is evident that great delay in operation from fire must ensue when the initial temperature surrounding the head is at low points, zero or below—as may be frequently found in freezers or non-heated places. Hence, all typical sprinkler heads as at present constructed and operated are unreliable for high and abnormally slow for low temperatures.

The operating records of sprinkler systems clearly show the great need of a dependable apparatus capable of quicker operation from all fires and especially at the

beginning of the fire; it being evident that the quicker water is directed on the fire the less the loss. To do this a sprinkler head is needed sensitive enough to operate 5 on what is known as a one-head fire (i. e., a fire small enough to be extinguished with the water from one head). This is only possible by a head constructed so as to be supersensitive to heat, operating at a pre- 10 determined rate of rise in temperature, also without lag and indifferent to the state of the initial temperature, instead of one so constructed that it is necessary to wait for the temperature to rise to a fixed or determined degree with inherent lag and consequent delay in action.

The object of my present invention is to overcome the defects in sprinkler heads above set forth and secure the advantages 20 indicated to which end the solder or alloy for holding the movable arm or system of arms connected to the fluid retaining cap is discarded and the apparatus is so constructed that the desired operation of 25 the sprinkler head is produced by the action of a rate of rise thermostat, all as will be more particularly set forth. The rate of rise thermostat may be of the type in which the operative member for the 30 above purpose consists of a diaphragm exposed to the pressure of air or other fluid heated in a chamber which is provided with a regulated vent for the air, gas or other fluid, whereby the sprinkler head will operate by release of its cap restraining arm whenever the temperature advances at or 35 beyond the desired rate of rise per unit of time.

In the accompanying drawings: 40 Fig. 1 is a partial vertical section and side elevation of one form of an apparatus constructed in accordance with my invention and shows the invention.

Fig. 2 is a section on the line 2—2 of 45 Fig. 1, at right angles to Fig. 1; and

Fig. 3 is a plan of a part of the thermostat mechanism.

The invention will be described in connection with a particular form of sprinkler 50 head from which its application to other forms will be readily understood by those skilled in the art.

O in the accompanying drawings indicates the body of a metal frame of a sprinkler head threaded at the bottom to screw into the pipe fitting and N indicates the cap or valve through which the fluid may flow under the pressure in the sprinkler system for extinguishing a fire. Said cap or valve 55 in one form of sprinkler heads seats, as indicated, on a diaphragm u exposed also to pressure in the piping system. P is the upper part of the frame rising from the base O of the frame and the top of the 60 frame carries a suitable deflector or distrib-

uter E preferably arranged to distribute any fluid coming through the orifice opened when the cap or valve is thrown from its seat. F is a supplemental deflector or distributor which may be used for fluid escaping through or by the deflector E. K is an arm extending up from the cap or valve and receiving pressure therefrom under the action of pressure in the piping and L is another arm having a bearing at its upper 70 end against the upper portion of the frame and engaged at its lower end by an offset on the arm K, the two arms forming in effect struts which are so arranged with relation to the line of pressure that the cap or valve will be thrown off its seat by the pressure unless the arm K is held in restraint. If the arm K is freed the two arms are thrown apart and the cap flies from its seat, thus permitting the fluid to flow.

According to my present invention the arm L is held against movement by a restraining device consisting of an arm or lever J mounted on a pintle J' at the top 80 of the frame of the sprinkler head. The depending end of the arm J is located in position to normally restrain or hold the arm K against movement so long as the arm J is itself held against movement, through a system of levers controlled, as will be 85 presently described, by the action of the operative member of a rate of rise thermostat. For the sake of convenience in assembling the device, the upper end of the arm K is provided with a locking clip M pivoted to be capable of turning on the face of the arm K, so as to bring its end into position to engage with the end of the arm J after the arm L has been turned back 90 into position to seat the valve N.

The rate of rise thermostat may be constructed as follows:

C indicates a diaphragm secured in place 95 between two halves D D' of a metal container and dividing said container into two sealed spaces A and B enclosing each a body of air. The half D' of the metal shell is preferably made of thicker metal than D or is otherwise constructed so that the air in space B will be heated more rapidly than the air in space A under the effect of changes of temperature in the air or medium surrounding the container. Hence, under the influence of rises of temperature, the diaphragm C will be caused to move in 100 a direction away from the space B. To govern this movement of diaphragm C and to restrict the movement of C in response to predetermined rates of rise of temperature produced under normal conditions, equalizer vent V is made in diaphragm C. By properly proportioning the size of this vent or hole in C, any difference of pressure between A and B due to temperature 105 advances and retardation due to difference 110 115 120 125 130

in mass of shells D and D' may be governed and diaphragm C made to move in the desired direction when pressures build up in B in response to rapid rates of rise of 5 temperature beyond equalizing factor of vent V and arising from abnormal conditions. At rates of rise in temperatures below the compensating setting of vent V pressures equalize on opposite sides of 10 diaphragm C and there is not enough pressure and consequent movement of C to release the leverage system. When the required movement of C is reached, it releases train of levers I, J, M, K and L, permitting cap N to leave its seat in U, in response to pressure of water in the piping system; this train of levers being one of the many ways that may be employed to accomplish the same end, viz to free the cap 15 N from restraining forces.

The lever I of the above-named system of levers is suitably connected with the center of the diaphragm C by a pin or piece H extending therefrom, said lever I being constructed with a pintle S or pivot pin mounted on one face of a plate G and with a depending arm arranged to normally lie in the path of the upper arm of lever J. When the lever I moves by the action of 20 the operating member C of the air thermostat its lower end moves to one side of the upper end of arm J, thus freeing or tripping the same so that it will no longer restrain the lever K and the valve N will leave its seat.

A stop or limit device consisting, for instance, of plate G open at its centre, serves to limit the action of diaphragm C in response to sudden drop in temperature, thus 40 avoiding dislodging trip or lever I. Should the temperature advance more slowly than the predetermined rate, the apparatus might fail to operate due to the advance being slower than the compensating setting, so that fire might take place without release of the valve. To avoid this contingency a supplemental diaphragm C' is provided which is also subject to the air pressure within the thermostat and is operatively connected with the lever I by means of the hook H' hooking into an arm H attached to the diaphragm C or by other suitable means. The hook H' engages with the arm H through a slot or opening therein providing a space which allows for lost motion, so that there will be no interference with the normal action of diaphragm 45 C. This diaphragm C' is considerably stiffer than C and moves only when the accumulated pressure in A and B overcomes its inertia. Under slow rises in temperature air in A and B equalizes through vent V with less difference of pressure than is necessary to move diaphragm C to operating point and this state could continue to

melting point, unless diaphragm C' was in the system. C' is stiff enough to resist all operating pressures caused by rises in temperature up to the rate of rise setting. It will, however, operate whenever the predetermined degree of temperature is reached, 70 due to the expansive force of air in A and B operating on C'. Either diaphragm in operation releases the intervening levers opening the head. Deflector F is arranged 75 to spread water properly above the ball D D'.

To make air chamber A-B tight and sealed to atmosphere, also permit assembly and adjustment of the train of levers, the 80 open passage through upper part of frame P may be sealed and made flexible and leak-proof in any desired way as for instance by sealing it by flexible diaphragm 2, such as gold beater skin, having metal washer 85 support below with sealed or restricted opening through which passes lower end of lever or crank J. This metal washer enables said sealing diaphragm to safely withstand all pressures in A and B met 90 with in practice.

By this construction my improved sprinkler head has the dual feature of operating upon a rate of rise as well as upon a fixed temperature principle, thus guarding 95 against failure to operate by a rate of rise of temperature per unit of time, slower than the compensating setting of the rate of rise portion of the apparatus. Obviously, therefore, I retain by my invention not only all 100 the advantages of the present constructions of sprinkler heads, but remove many of the objections due to the presence of fusible members and by the combination of the two principles of heat detection without the use 105 of fusing devices, I secure by one unit results hitherto unattainable.

It will be noticed that the vent V operates as an equalizer between two air spaces, said vent and both air spaces being sealed to the atmosphere. This construction removes the danger of vent and moving members being affected by corrosion or encrustation, if the apparatus should be installed, for instance, 110 in a chemical, cement or sugar establishment. This feature, together with the further enclosing of all operating detents within a sealed space ensure a complete mechanism that will be free from all liability of 115 change of operating constant due to loading effect of a deposit of viscous or other retarding foreign matter.

To seal the space containing the operating members L, M, and valve, a casing rupturable by the force of the fluid escaping through the valve may be employed. T indicates a casing of this nature made preferably of glass or other translucent material, and in sections W indicates one of the dividing lines between sections. The 125 130

casing rests upon a ledge of the base O as shown and at this point may be held lightly by a cement that will soften by heat or by other means allowing the sections to fall 5 apart when they are struck by the water flowing from the valve.

A sprinkler head made according to my invention will operate as promptly in cold storage rooms as in heated rooms—such 10 action always being without appreciable retardation, or delay, and permits of one type of head for all temperatures.

Also a sprinkler system equipped with this improved head operating by rate of 15 rise of temperature will give greater range of fire detection and will materially lower the loss from fire and water and also greatly reduce the present sprinkler protection cost owing to one type of head only being 20 needed for all conditions, while because of its greater sensitiveness smaller fluid supply and conveying pipes are allowable and fires may be controlled with less number of heads per given floor area to be protected.

25 While I have described the use of "air" in the chambers it will be understood that any gas or fluid might be used and that the term "air" in this specification and subjoined claims is to be taken as a generic 30 term including any fluid expansible by heat.

By the term "rate of rise temperature thermostat" as employed in the appended claims, I mean:

(1) Adapted to act primarily in response 35 only to changes of temperature occurring at a predetermined rate greater or quicker than the normal rate of change of temperature of the atmosphere permissible without operation of the sprinkler head in contradistinction to one like one having a fusible member which will act only upon the attainment of a fixed or absolute temperature reached indifferently through any rate of change.

40 45 What I claim as my invention is:—
1. The combination of a sprinkler head cap or valve, means restraining said cap and a rate of rise of temperature thermostat adapted to release said restraining means.

50 55 2. The combination of a sprinkler head frame, a cap or valve, means restraining said cap or valve, and means for releasing said cap or valve actuated by a rate of rise of temperature thermostat.

60 5. The combination with the cap or valve restraining means of a sprinkler head, of a rate of rise temperature actuated releasing means therefor.

65 4. A fluid distributing device having a closure therefor, combined with means for opening said closure actuated by a rate of rise of temperature thermostat.

5. The combination with a fluid distributing device and a closure therefor, of

means restraining said closure and means of releasing said restraint comprising a rate of rise of temperature thermostat.

6. A fluid distributing device and a closure therefor, combined with means for opening said closure actuated by the rate of rise of temperature.

7. The combination with the cap or valve holding arm or lever for a sprinkler head by which the outlet valve is held normally 75 in place, of a restraining device normally engaging and locking said arm, a rate of rise thermostat and means mechanically connected with the operative member of said thermostat for freeing said restraining device.

8. The combination with a cap or valve locking lever for a sprinkler head, of a fluid thermostat having a diaphragm and equalizing vent exposed to pressure of the 85 fluid therein and adapted to respond to a predetermined rate of rise of temperature and means controlled by said diaphragm for releasing the sprinkler head arm or lever to allow the valve to open.

9. The combination of a sprinkler head and cap or valve holding lever therefor, means for restraining the action of said lever, an air thermostat having a sealed air space and two diaphragms exposed to air pressure within said space generated by changes of atmospheric temperature and means controlled by said diaphragms for releasing the cap restraining arm, one of 95 said diaphragms being set to respond to pressure by which the other remains unaffected as and for the purpose described.

10. The combination with a sprinkler head and the cap restraining arm or lever therefor, of an air thermostat comprising 105 an air receptacle having two chambers connected by an equalizing passage and separated by a diaphragm and means controlled by said diaphragm for releasing the cap restraining arm or lever.

11. The combination of a sprinkler head and its cap holding arm or lever, of a locking device adapted to hold or restrain said arm or lever to keep the valve closed and an air thermostat having two thermostatically actuated devices both operatively connected with said restraining device, one of said devices acting only by pressure adjusted to rate of rise of temperature and the other set to act only on attainment of a fixed temperature and consequent pressure above that required to operate the first.

12. The combination with the valve holding arm or lever of a rate of rise thermostat, comprising a plurality of sealed chambers the walls of which are of different heat conducting capacity, a diaphragm exposed at opposite sides to the air pressures within said chambers respectively, a restraining arm normally holding the valve arm against 125 130

movement and a tripping lever operated by the action of the diaphragm to release said restraining arm.

13. The combination with the valve arm or lever for a sprinkler head and a restraining device normally engaging and locking said arm, of a rate of rise thermostat and mechanism actuated thereby for freeing said restraining device and a supplemental thermostatic device having means for mechanically actuating said mechanism and responsive only to excessive temperature reached by a rate of rise slower than that required to operate the rate of rise portion of the thermostat.

14. The combination with the valve arm or lever for a sprinkler head, of a restraining device and an air thermostat having two diaphragms operatively connected with said restraining device, one of said diaphragms acting by pressure resulting from a predetermined advance of temperature per unit of time and the other set to act only on attainment of a pressure above that operative in freeing the cap or valve by the operation of the first-named diaphragm.

15. In a sprinkler head, the combination of a frame or section for attaching to piping, a valve cap, restraining means holding said valve cap in position, and a rate of rise

thermostat having a plurality of air chambers separated by a diaphragm common to all and fitted with an inter-connecting equalizing passage, sealed from the atmosphere and means connected with the operated member of said thermostat for freeing said restraining device. 35

16. In a sprinkler head, a fluid restraining member held in a closed or inoperative position by restraining means actuated by the rate of advance of heat in a plurality of fluid retaining chambers, the walls of which have different mass. 40

17. In a sprinkler head, the combination of a frame or section for attaching to piping, a valve cap, levers or arms holding said valve cap in position, a restraining device normally engaging and locking said levers or arms, a rate of rise thermostat and means connected with the operative member of said thermostat for freeing said restraining device. 45
